United States Patent Office

Des. 212,422
Patented Oct. 15, 1968

212,422

TRANSCRIBER OR THE LIKE

Eliot F. Noyes, New Canaan, Conn., assignor to International Business Machines Corporation, Armonk, N.Y., a corporation of New York

Filed Dec. 7, 1967, Ser. No. 9,677

Term of patent 14 years

(Cl. D26—14)

FIG. 1

FIG. 2

FIG. 3

FIG. 4

FIG. 5

FIG. 6

FIG. 7

FIG. 1 is a right front perspective view of a transcriber or the like illustrating my new design;

FIG. 2 is a left rear perspective view thereof;

FIG. 3 is a top plan view thereof;

FIG. 4 is a front view thereof;

FIG. 5 is a rear view thereof;

FIG. 6 is a left elevation thereof; and

FIG. 7 is a right elevation thereof.

The dominant features of my design reside in the portions shown in full lines.

I claim:

The ornamental design for a transcriber or the like, substantially as shown and described.
